UNITED STATES PATENT OFFICE.

ALEXANDER E. PALUCK, OF BELFIELD, NORTH DAKOTA, ASSIGNOR OF ONE-HALF TO
STANISLAUS J. CIESLEWICHS, OF WIBAUX, MONTANA.

FIGURE TOY.

Application filed July 15, 1927. Serial No. 206,067.

This invention relates to toys and its general object is to provide a figure toy of the self propelling type that is capable of walking and moving an object secured thereto accordingly.

A further object of the invention is to provide a self propelled walking toy that is possessed of long life, is extremely simple in construction, inexpensive to manufacture, 10 strong and durable and is efficient in operation and service.

This invention also consists in certain other features of construction and in the combination and arrangement of the several parts, to 15 be hereinafter fully described, illustrated in the accompanying drawings and specifically pointed out in the appended claims.

In describing my invention in detail, reference will be had to the accompanying drawings wherein like characters denote like or 20 corresponding parts throughout the several views, and in which:

Figure 1 is a side elevation of the toy forming the subject matter of the present invention, with parts broken away and in section.

Figure 2 is a longitudinal vertical sectional view taken through the toy with parts in elevation.

Figure 3 is a sectional view taken on line 30 3—3 of Figure 1, looking in the direction of the arrows.

Figure 4 is a slightly modified form of a foot for the toy.

While I have illustrated my toy constructed in the form of a walking doll with a wheeled object secured thereto, it will be obvious that it can be constructed to simulate animals and the like, without departing from the spirit of the invention.

40 Referring to the drawings in detail the reference numeral 1 indicates the body of the toy as shown and which is hollow with a head 2 formed therewith as best shown in Figure 1 of the drawings. Formed with the body 1 upon opposite sides thereof are arms 3 which terminate in hands 4 at their lower ends.

Secured in the body is a frame which includes parallel uprights 4 and 5 having their 50 upper ends bent upon themselves and fixed to the shoulders of the body as best shown in Figure 2. The uprights 4 and 5 have their lower ends enlarged to provide plates 6 between which is mounted a spring motor 7 of the usual construction and which includes a

spiral spring 8 secured to a shaft 9 which is rotated for winding the spring through the instrumentality of a key 10 secured to the projecting end of the shaft 9. Fixed to the shaft 9 is a gear 11 arranged in mesh with a pinion 12. The pinion 12 is fixed to a shaft 13 which has its ends mounted for rotation in the plates above the shaft 9 and secured to the ends of the shaft 13 which are arranged upon opposite sides of the plates 6 are disk wheels 14 which have extending outwardly therefrom and eccentrically mounted thereon pivot pins 15.

Passing through the body 1 adjacent its lower end is a rod 16, and said rod is secured to the body in a manner to prevent transverse movement thereof through the medium of heads 17. Pivotally secured to the rod 16 are the upper ends of the legs for the body, and these legs are formed in two parts, namely, an upper part 18 and a lower part 19. The upper or thigh parts of the legs are bent upon themselves in order to provide the enclosed construction as shown, and pivotally mounted adjacent the lower ends of the upper or thigh part of the legs 18 are the lower parts 19 which are likewise formed in an enclosed manner, but have their lower ends open in the same manner as the upper parts 18 in order to pivotally receive the feet 20 as best shown in Figure 1 of the drawings.

The uprights 4 and 5 are provided with slots 21 arranged longitudinally therein and adjacent their upper ends. Arranged upon opposite sides of the uprights and plates which form the frame are levers 22 which have headed studs 23 secured to their upper ends and mounted in the slots for slideable movement. The levers 22 are secured intermediate their ends to the pivot pins 15, and extend through the enclosed portion of the upper or thigh part 18 of the legs and terminate in the lower parts 19. The lower end of the levers 22 are pivotally secured in the lower parts of the legs and projecting from adjacent the lower ends of the levers is a hook 24 which receives one end of a coil spring 25 while the opposite end of the coil springs 25 are secured to the feet 20 for a purpose which is apparent.

Any type of wheeled object may be secured to the body and I have shown a wheeled frame 26 with handles 27 formed therewith and which extend through the body and are secured to projections 28 extending forwardly

and at a downward inclination from the uprights 4 and 5.

In Figure 4 I have illustrated a slightly modified form of foot which for the purpose 5 of distinction is indicated by the reference numeral 29 and the foot in this form is provided with a weighted rear portion 30 with the result that when this foot is used with the 10 toy, the coil springs can be dispensed with, as it will be obvious that the weight will cause the foot to assume an inclined position due to the action of gravity thereon.

From the above description and disclosure 15 of the drawings, it will be obvious that by winding the spiral spring upon its shaft 9 through the instrumentality of the key 10, that power created by the unwinding of the 20 spring will cause the shaft 9 to rotate, such rotation will be imparted to the shaft 13 and to the disk wheels 14 which will cause the levers 22 to reciprocate. Due to the fact that the levers have their lower ends secured to the 25 lower parts 19 of the legs, the legs will likewise be given a reciprocating movement and cause the toy to walk by lifting the lower 30 parts of the legs as suggested in Figures 1 and 2 of the drawings. Upon lifting the legs, the coil springs will cause the feet to be arranged at an upward inclination so as to give the toy the desired effect of walking.

It is thought from the foregoing description that the advantages and novel features of my invention will be readily apparent.

I desire it to be understood that I may make 35 changes in the construction and in the combination and arrangement of the several parts, provided that such changes fall within the scope of the appended claims.

What I claim is:

40 1. A toy of the character described comprising a body including shoulders and a head, jointed legs pivotally secured to said body, feet pivotally secured to the legs, a frame in said body, parallel arranged up- 45 rights included in said frame and having their upper ends bent upon themselves and secured to the shoulders, plates formed with said uprights, a spring motor secured between said plates, levers mounted for reciprocation 50 and connected with said uprights and the legs, means operated by said spring motor to reciprocate said levers for moving said legs, and springs having their end convolutions secured to the lower ends of the levers and feet re- 55 spectively for moving the feet upon the movement of said legs.

2. A toy of the character described comprising a hollow body, a head formed therewith, jointed legs including upper parts, lower parts pivotally secured to the upper parts, feet pivotally secured to the lower parts, a frame disposed in said body, parallel uprights included in said frame and being provided with slots at their upper ends, plates formed with the lower ends of said uprights by enlarging the said ends thereof, a spring motor disposed between the forward portions of said plates, means for pivotally securing the upper parts of the legs to the rear portions of said plates a shaft crossing said plates 70 and having its ends projecting upon opposite sides thereof, disk wheels secured to said projecting ends, levers extending into said body and legs, means including headed studs secured to the upper ends of said levers and arranged in said slots for reciprocation for mounting the levers accordingly, means for eccentrically mounting said levers to said disk wheels, and said levers having connection 75 with said feet.

3. A figure toy of the character described comprising a hollow body, a head formed therewith, arms and hands included in said toy, jointed legs including upper parts pivotally secured in said body, lower parts pivotally secured to said upper parts and having their lower ends open, feet pivotally secured to said lower parts and being movable in the open lower ends thereof, a frame disposed in said body and including uprights, projections extending forwardly at an inclination from said uprights, plates formed with said uprights, a spring motor arranged between said plates, a shaft crossing said plates and having its ends projecting upon opposite sides thereof, disk wheels secured to the projecting ends of said shaft, levers having their upper ends secured to said uprights for reciprocation, hooks extending from the lower ends of said levers, pivot pins eccentrically secured to said disk wheels and pivotally receiving said levers, means for securing the lower ends of said levers to the lower parts of said legs, a gear fixed to said shaft and operated by said spring motor for reciprocating said levers and legs accordingly, means secured to said hooks and feet respectively for raising said feet upon movement of said legs and a wheeled frame secured to said hands and projections.

In testimony whereof I affix my signature.
ALEXANDER E. PALUCK.
